[57] **CLAIM**

The ornamental design for a fabric blind, as shown and described.

DESCRIPTION

FIG. 1 is a fragmentary perspective view of one side and end of a first embodiment of a fabric blind;

FIG. 2 is a fragmentary perspective view of one side and end of a second embodiment of a fabric blind;

FIG. 3 is an enlarged fragmentary perspective view of the upper side and intermediate portion of one of the slats of the fabric blind;

FIG. 4 is a side view of FIG. 3;

FIG. 5 is a greatly enlarged end view of one of the slats of the fabric blind, the opposite end being a mirror image;

FIG. 6 is a perspective view of the lower side of FIG. 3; and, FIG. 7 is a greatly enlarged fragmentary perspective view of the upper side of one of the slats of the fabric blind at an end thereof, with the rods in alternate position.

The fabric blind is shown broken away in FIGS. 1 and 2 to indicate intermediate length and width, it being understood that the pattern repeats uniformly along its length and width, and the opposite end is the same as that shown.
